UNITED STATES PATENT OFFICE.

GEORGE G. GAREY, OF INDIANAPOLIS, INDIANA.

HEATING STOVE AND FURNACE.

1,139,857.

Specification of Letters Patent. Patented May 18, 1915.

Application filed June 22, 1914. Serial No. 846,632.

To all whom it may concern:

Be it known that I, GEORGE G. GAREY, a citizen of the United States, residing at Indianapolis, in the county of Marion and State of Indiana, have invented a new and useful Heating Stove and Furnace, of which the following is a specification.

This invention relates to heating stoves and furnaces, and more particularly to a novel form of fire pot and base whereby, when the heater utilizes a down draft for supporting combustion, the combustion products are directed through the wall of the fire pot and subsequently commingled with fresh warm air admitted to the base and around the ash pit where combustion is completed and the walls of the base or ash pit thoroughly heated so as thus to add to the heating surface of the stove or furnace and, consequently, increase its efficiency.

A further object is to provide a fire pot having a novel arrangement of air channels whereby the currents produced by the down draft through the fuel will be distributed to the various air passages, said passages being so shaped as to prevent ashes and other products of combustion from lodging therein and thus interfering with the flow of gases from the fire pot.

30 A further object is to so arrange the outlets of the air passages relative to the fresh air inlets in the base as to cause a thorough commingling of the gases within the base where final combustion will take place.

35 With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

45 In the accompanying drawings the preferred form of the invention has been shown.

In said drawings:—Figure 1 is a central vertical section through the heater, the top being shown partly in elevation. Fig. 2 is a section on line A—B Fig. 1. Fig. 3 is a section on line C—D Fig. 1. Fig. 4 is a vertical transverse section through a portion of the base.

55 Referring to the figures by characters of reference, 1 designates the supporting legs

on which is mounted an ash pit 2 having a smoke flue 3 extending upwardly therefrom preferably at the rear thereof. The ash door 4 is arranged in front of the ash pit as ordinarily and extending across the back portion of the ash pit is a partition 5 while additional partitions 6 extend within the side portions of the ash pit from the front thereof to the ends of the cross partition 5. These side partitions 6 have flanges 7 along the upper edges thereof which are inclined upwardly and outwardly and thus constitute means for deflecting ashes into the space between the door 4 and the transverse partition 5. It will be noted also, by referring to Fig. 1, that the transverse partition 5 has an upper inclined portion 8, which however, extends up to the wall of the ash pit. The partitions coöperate with the walls of the ash pit to form a flue or supplemental combustion chamber 9 opening into the lower end of the outlet flue or smoke pipe 3. An ash pan 10 may be removably mounted within the ash pit.

50 An annular air conduit or distributing flue 11 is formed in the top portion of the ash pit 2 and extends around the fire pot 12. Another air conduit or flue 13 extends around the upper portion of the fire pot 12. The conduit 13 has an air inlet 14 adapted to be closed by a suitable damper 15, this inlet and damper being arranged preferably upon the front portion of the conduit 13. The lower air 55 flue or conduit 11 has an air inlet opening 16 adapted to be partly or entirely closed by a damper 17. Air ports 18 are formed in the inner wall of the conduit 11 and additional air ports 19 are formed in the inner 60 wall of the conduit 13.

55 The fire pot 12 fits snugly upon the top of the ash pit and is tapered downwardly, the fire pot being provided upon its outer face, with hollow ribs 21 forming air flues. 65 Longitudinal slots 22 are formed in the wall of the fire pot and open into the respective flues 21, these slots extending from the upper edge of the fire pot and down to points spaced from the grate 23 supported within 70 the lower portion of the fire pot. Each slot 22 is gradually widened at its lower end, as shown at 24, the width of the lower end of each widened portion being substantially 75 equal to the width of the air passage or flue 110 with which it communicates. The flues 21 do not terminate at the lower ends of the

slots 22 but continue downwardly to the lower edge of the fire pot 12, that portion of each flue 21 between the slot 22 and the lower edge of the fire pot being gradually 5 widened downwardly, as indicated by dotted lines at 25 in Fig. 1. Furthermore as indicated in said figure the fire pot projects downwardly into the top of the ash pit, said fire pot being supported in such position 10 by frictional engagement of the flues 21 with the upper surface of the ash pit. The lower or outlet ends of the flues 21 are cut off or substantially beveled so as to extend from the top of the ash pit downwardly and 15 inwardly to the lower edge of the fire pot, thus forming substantially arched openings 26 at the lower ends of the flues 21. These openings 26 are disposed directly opposite the ports 18 so that any products of combustion passing downwardly through the outlets 26 will promptly commingle with air discharged through the ports 18 into the space between the flue or conduit 11 and the depending portion 27 of the fire pot. Ribs 28 are formed upon the inner surface of the fire pot 12 between the upper portions of the slots 22, these ribs having downwardly and inwardly inclined upper faces and constituting means for preventing fuel from 20 packing into the slots 22. By inclining the upper ends of the ribs 28, fuel, ashes, etc., 30 will not become lodged thereon.

The grate 23 can be of any desired form but is preferably of the close-up type having 35 a central opening 29 adapted to be closed by a slide 30, the grate being dished and adjustable for use either with an up-draft or a down-draft, it obviously being desirable to open the grate when used with an up-draft and to close it when a down-draft is used.

Mounted on the fire pot 12 is a casing section 31 supporting the top section 32 which may be provided with the usual dome-shaped cover 33 extending over a feed hopper 34. An outlet flue 35 extends from the top portion of the heater and opens into the upwardly extending flue 3, there being a damper 36 of any suitable form whereby the flue 35 can be closed while the down-draft is being used.

Arranged within the upper portion of the casing section 31 is a diaphragm 37, having marginal flanges 38 bolted or otherwise secured to the heater casing and said diaphragm, which is preferably frusto-conical, has recesses 39 cut into the marginal portion thereof whereby outlet openings are formed between the diaphragm and the wall of the heater casing through which products of combustion are free to flow while an up-draft is being used. By providing these outlet openings at the points indicated and as shown particularly in Fig. 3, the products 60 of combustion ascending within the heater 65

will travel close to the wall of the casing and thus raise the temperature of the wall to a higher degree than would otherwise be the case. The bottom of the diaphragm 37 has an opening 40 adapted to be closed 70 by a slide 41 which can be actuated by means of a rod 42 extending through the heater casing. This rod as well as the slide is adapted to work within a slot 43 in the wall of the diaphragm. Obviously by pulling the 75 slide 41 forwardly, the opening 40 will be partly or entirely uncovered, thus permitting fuel to gravitate from the hopper 34 and diaphragm 37 into a magazine 44 which is supported by the diaphragm 37 and around the opening 40. This magazine does not constitute any part of the present invention but has been described and claimed in detail in a copending application filed by me on February 24, 1913, Serial No. 750,378. 80

The heater herein described can be used both as an up-draft heater and as a down-draft heater. When used in connection with an up-draft, the grate 23, which, as hereinbefore stated, can be of any preferred construction, is regulated so as to allow air to flow therethrough and upwardly through the fuel, thus causing the products of combustion to circulate along the inner surface of the wall of the heater casing and thence through the outlet 39 to the flue 35. A certain percentage of air will be admitted to the fuel by way of the flues 21 and the slots 22, thus causing as complete combustion of the fuel close to the wall of the fire pot as takes place at the center of the fire pot. However, the present improvements reside primarily in those features which enable a down-draft to be used efficiently. In using the down-draft the grate 23 is closed and the damper 36 is likewise closed. The inlets 14 and 16 are opened and the fuel ignited within the fire pot 12. Combustion is supported primarily by air admitted to the fuel through flues 45 formed along the 90 wall of the magazine 44, these flues having inlets at any suitable points and which have not been shown. The current of air passing downwardly through the fuel will split and move into the slots 22, the larger lower ends of the slots indicated at 24, serving to draw the air and combustion products downwardly toward the lower ends of the slots where said products will enter the flues 21. A certain amount of fresh air will enter the fuel by way of the conduit 13, ports 19 and the upper portions of the slots 22 thus supporting combustion close to the wall of the fire pot. When the products of combustion issue from the arched openings 26, they mix with the fresh air admitted through the ports 18, this mixture flowing downwardly into the combustion flue 9 where combustion is completed, the unconsumed products then 95 passing out through the flue 3. 100

Importance is attached to the fact that the lower end portions of the flues 21 are widened downwardly so that any ashes which may be carried in the flues will not 5 become lodged therein but will gravitate into the ash pit.

What is claimed is:—

1. The combination with an ash pit having an air conduit at the top thereof, said conduit being provided with an air inlet in its outer wall and air outlets in its inner wall, of a fire pot bearing downwardly on the ash pit and projecting thereinto, ribs upon the outer surface of the fire pot and forming air flues discharging into the space between the conduit and that portion of the fire pot projecting into the ash pit, and a grate supported within the fire pot, said fire pot having slots in the upper portion of the wall thereof and communicating with the respective flues thereby to direct gases into the upper portion of the fire pot and on top of the fuel contained within the fire pot, said slots terminating at points above and 25 spaced from the grate, the lower ends of the slots being widened downwardly, the greatest width of each slot being equal to the width of the interior of the flue with which it communicates.
2. The combination with an ash pit having an air conduit at the top thereof, said conduit being provided with an air inlet in its outer wall and air outlets in its inner wall, of a fire pot bearing downwardly on the ash pit and projecting thereinto, ribs upon the outer surface of the fire pot and forming air flues discharging into the space between the conduit and that portion of the fire pot projecting into the ash pit, and a 35 grate supported within the fire pot, said fire pot having slots in the wall thereof and communicating with the respective flues, said slots terminating at points above and spaced from the grate, the lower ends of the slots 40 being widened downwardly, those portions of the flues below the slots being gradually enlarged downwardly.
3. In a heating stove the combination with an ash pit and an air conduit at the top thereof and provided with an inlet in the outer wall thereof and outlets in its inner wall, of a fire pot bearing upon the ash pit and extending downwardly thereinto, said fire pot having air flues on the outside thereof, said flues discharging into the space between the lower portions of the fire pot and

the apertured wall of the conduit, a conduit extending around the upper portion of the fire pot and having an inlet in its outer wall and outlets in the inner wall, said outlets opening into the flues, there being slots within the wall of the fire pot and extending longitudinally of the respective flues, the lower end portions of the slots being gradually widened downwardly and terminating 65 between the ends of the flues, those portions of the flues between the slots and the bottom of the fire pot being gradually widened downwardly.

4. In a heater, the combination with an ash pit and a conduit at the top thereof and discharging into the ash pit, said conduit having a valved air inlet, of a fire pot supported by the ash pit and projecting downwardly thereinto, ribs upon the outer side 75 of the fire pot and forming air flues discharging into the space between the conduit and the lower end portion of the fire pot, openings in the wall of the fire pot and discharging into the respective flues, an outlet 80 flue extending from the ash pit, a transverse partition extending across the inlet of said outlet flue, and side partitions extending from the ends of the transverse partition and forwardly within the ash pit, said partitions and the walls of the ash pit coöperating to form a combustion chamber for the reception of gases mixed between the conduit and the lower ends of the flues on 85 the fire pot.

5. In a heater, a fire pot formed in a single casting and having exterior ribs extending from the upper to the lower edge thereof and provided with air flues therein, there being a conduit discharging into the upper 95 end portions of the flues, said flues being open at their lower ends, there being slots in the wall of the fire pot and opening into the respective flues, said slots extending longitudinally of the flues and having their lower end portions gradually widened to the width of the flues, those portions of the flues below the slots being gradually widened 100 downwardly toward their open ends.

In testimony that I claim the foregoing 105 as my own, I have hereto affixed my signature in the presence of two witnesses.

GEORGE G. GAREY.
